SHOE SEWING MACHINE

Edward Quinn, Malden, Mass., assignor to United
Shoe Machinery Corporation, Flemington, N. J.,
a corporation of New Jersey

Application March 12, 1941, Serial No. 382,905

9 Claims. (Cl. 112—62)

The present invention relates to shoe sewing machines, and more particularly to machines adapted for sewing the upper to the sole of a shoe unsupported on a last.

The invention is herein disclosed as embodied in a straight needle overarm sewing machine of the general type having stitch forming devices which include a work piercing awl, and a straight needle movable to feed the work, and devices arranged for guiding and for supporting the work in position to cause the needle to enter and to emerge from the same side of the work, which include a work support adapted to enter the stitch receiving channel formed in the sole, a presser foot to bear against the upper against the edge of the sole, an upper guard, and preferably a horn arranged to extend within the shoe and bear against the inner surface of the sole at the sewing point.

The illustrated machine is similar in many respects to that illustrated in the patent to Quinn et al., No. 2,198,391, dated April 23, 1940, and is similarly adapted for operation upon turn shoes or slippers in which the upper has been temporarily attached to the sole for inserting a row of stitches through the upper and between-substance between a shoulder adjacent the sole edge and a stitch receiving channel formed on the same side of the work.

It is the object of the present invention to improve the construction and arrangement of the devices for supporting and for positioning the work to permit greater latitude in the use of the machine for sewing upon shoes or slippers constructed from thin or fragile materials and to permit of the most advantageous location of the several positioning and actuating devices in accordance with the requirements of the work being operated upon.

With this and other objects in view as may hereinafter appear, certain features of the invention relate to the provision of an improved construction and mode of operation of the mechanism for actuating and for positioning the upper guard.

Another feature of the invention consists in the provision in a machine of the general type described, of a novel and improved work support better adapted for supporting the work against the thrust of the awl, particularly where it is attempted to sew shoes or slippers composed of extremely thin or fragile materials.

The several features of the invention consist also in the combination, devices and arrangement of parts hereinafter described and claimed, which

together with the advantages to be obtained thereby will be readily understood by one skilled in the art from the following description taken in connection with the accompanying drawing, in which Fig. 1 is a partial view in left side elevation of a straight needle sewing machine embodying in a preferred form the several features of applicant's invention, only so much of the machine being illustrated as is believed necessary to illustrate the connection of the present invention therewith; Fig. 2 is an enlarged detail view partly in section and with the presser foot and portions of the supporting structure broken away to illustrate particularly the upper guard and its actuating positioning means; Fig. 3 is a view in rear elevation taken on the line 3—3 of Fig. 2; Fig. 4 is a detail view in front elevation illustrating particularly a modified form of work support adapted for use on certain types of work; Fig. 5 is a plan view taken on the line 5—5 of Fig. 4, illustrating particularly applicant's improved work support; and Fig. 6 is a sectional view taken on the line 6—6 of Fig. 4, illustrating specifically the split presser foot.

The machine disclosed in the drawing as embodying in a preferred form the several features of the present invention, is a wax thread chain-stitch machine of the overarm type having a work support comprising two relatively movable channel engaging members 10 and 12 (see Figs. 1 to 3 inclusive), and a straight hook needle 14 located beneath the work, and a cooperating presser foot 16, awl 18 and looper 20 supported by the overarm generally indicated at 22 above the work. In accordance with the usual construction of these machines, the needle is mounted on a swinging support for movement in the line of feed to impart a positive step-by-step feeding movement to the work. The awl is secured to the lower end of a vertically reciprocating awl bar 23 mounted on the overarm 22. The present machine is particularly constructed and arranged for sewing a line of stitches around the margin of a turn shoe or slipper which is preferably assembled in a reverse position with the upper and lining attached thereto, cemented or otherwise temporarily secured to a shoulder formed in the edge portion of the sole. The shoe or slipper is placed in the machine with the sole in a sharply inclined position, so that the needle at its work piercing stroke will enter the stitch receiving channel in the shoe sole, and passing through the upper and lining in a groove formed by the shouldered edge of the shoe sole. The work is supported vertically against

the downward thrust of the awl 18 and against the work piercing and loop drawing strokes of the needle 14 between the work supports 10 and 12 engaging within the stitch receiving channel, and the presser foot 16 which engages the upper or lining as the case may be in the grooved edge portion of the shoe sole. Further in accordance with the usual construction, the machine is also provided with a shoe supporting horn 30 arranged to extend within the shoe and bear against the inner surface of the sole at the sewing point, and an upper guard member 32 which is movable in a vertical plane into and out of engagement with the shoe to correctly position the upper and lining in advance of the operation of the presser foot and stitch forming devices during the progress of the sewing operation about the margin of the shoe.

The presser foot member 16 is provided with a downwardly extending nib 34 which fits into the groove formed by the shoulder at the edge of the sole in the line of feed immediately adjacent to and on that side of the needle remote from the completed stitches of the seam. The presser foot is provided also with a movable sector or plate 36, as best shown in Figs. 3, 4 and 6 of the drawing, mounted to turn on a pivot 38 on the presser foot member 16, and provided with a downwardly extending nib 39 which is arranged to engage within the groove formed by the shoulder at the edge of the shoe sole in the line of feed immediately adjacent to and on that side of the needle toward the completed stitches of the seam. A small tension spring 40 connected at one end to the sector 36 and at its other end to a pin 41 on the presser foot member, operates to maintain the sector and work engaging nib 39 in operating position determined by the engagement of a pin 42 on the presser foot member 16 in a slot 43 formed in the sector 36. This construction of the presser foot provides a support for the work upon both sides of and immediately adjacent the needle during the upward thrust of the needle through the work. When the presser foot is lifted and the needle is moved to the left to feed the work, the sector 36 will yield against the pressure of its spring 40, and is then permitted to move back into place before the presser foot has again returned to its work engaging position.

The stitch forming and work feeding devices of the machine including specifically the needle, awl, looper and presser foot, are constructed and arranged to have the usual timing of these parts, and are actuated from driving connections which have been more fully set forth in the patent to Quinn, No. 2,142,966, dated January 3, 1939, and in the Quinn et al. patent above referred to, and are well known in the art. Inasmuch as these connections form no part of the present invention, only sufficient disclosure of the same has been made to indicate the general arrangement of the same in the machine.

The present invention is concerned with the improvement of the devices for supporting and for guiding the shoe with relation to the stitch forming devices, with reference particularly to the upper guard 32 with its supporting and actuating mechanism, and to an improved work support which will adapt the machine for use upon certain types of work in which extremely thin material is employed, and in which the stitch receiving channel of the insole is formed with a flap or ledge which extends outwardly substantially at right angles to the surface of the sole.

As illustrated in the drawing, the upper guard 32 of applicant's improved construction is formed on the lower end of a slide member 44 which is movable in a vertical plane in a guideway 46 toward and away from the work engaging position. The guideway 46 is formed in two vertically disposed brackets or plates 47 and 48 having forwardly extending ears 50 and 52 secured by screws 54 and 56 to a cover plate 58 on the overarm support 22. In applicant's improved construction, the brackets 47 and 48 are arranged to be adjusted in a forward and back direction in order to permit adjustment of the upper guard 32 transversely toward or away from the sewing point. To this end the ears 50 and 52 are provided with slotted portions such as that designated at 60 in dotted lines in Fig. 1, in the ear 52, to receive the clamping screws 54 and 56. The work engaging portion of the upper guard 32 comprises a flat plate which is sloped downwardly and rearwardly at an angle, the face thereof providing a broad upper engaging surface, the lower edge 62 of the upper guard 32 being arranged to bear against the upper at the front side of the presser foot, and extending a substantial distance in advance of the sewing point. There is also provided on the leading side of the upper guard 32, a flanged portion 64 which extends transversely across the line of feed substantially across the shouldered edge of the sole and attached upper. The flanged portion 64 serves the particular purpose of clearing the loose portions of the lining in advance of the sewing point to prevent possible injury to the lining from the operation of the stitch forming devices. In previous constructions exemplified by the Quinn et al. patent above referred to, the upper guard was held yieldingly in engaging contact with the work, and was moved to a predetermined raised position away from the work during each feeding operation of the shoe.

In the present instance the upper guard 32 is arranged to be moved to a predetermined low work engaging position which is adjustably determined in accordance with the requirements of the particular work being operated upon. The upper guard is thus adapted to force the adjacent portions of the upper and lining away from the sewing point without at the same time having any tendency to break down the marginal contours of the shoe depended upon for the proper placing of the stitching, or to force the shoe outwardly at the sewing point.

In accordance with the present invention, the mechanism for operating and for positioning the upper guard, has been modified to increase the effectiveness of this part, and to adapt the machine particularly for operation upon work consisting of light-weight or fragile materials. With the improved construction, the guard 32 is moved yieldingly in a downward direction to a work engaging position determined by engagement of the upper guard with a stationary stop on the machine. The position of this stop is adjusted by the operator in accordance with the requirements of the particular work being operated upon. With this arrangement, the upper guard while engaged with the work is nevertheless supported independently thereof, so that it is able to perform its function of forcing the edge portions of the upper and lining away from the sewing point without at the same time having any tendency to break down the marginal contours of the shoe depended upon for the proper placing of the stitch or to force the shoe outwardly at the sewing point. Further in accordance with the in-

vention, the mechanism provided for raising the upper guard during the work feed is arranged to be readily adjustable by the operator in accordance with the character of the work being operated upon to cause the upper guard to be raised only the minimum distance required to avoid interference with the work feed, while at the same time permitting the upper guard to perform its function of clearing loose portions of the upper or upper and lining from the path of the stitch forming devices while the work is being fed. In the illustrated construction, the upper guard 32 is moved yieldingly toward the work by means of a torsion spring 66 which is supported at one end on a pin 68 and at its other end against the upper end of the shank portion 44 of the upper guard 32. The limit of downward movement of the upper guard 32 toward the work is determined by the engagement of a lug 70 on the slide 44 with an abutment 72 on a U-shaped plate 74 secured to the rear sides of the brackets 47 and 48. In order to provide for adjustment of the limiting down position of the upper guard 32, the plate 74 is vertically adjustable, being secured in position by means of clamping screws 76 which extend through vertically slotted portions of the plate 74 as best shown in Fig. 3.

Upward movement of the upper guard 32 is effected during that portion of each stitch forming and work feeding cycle of the machine during which the work is fed, by means of an actuating lever 78 loosely supported to turn on a stationary pivot pin 80. A small tension spring 82 secured at one end to a pin 84 on the hub of the lever 78, and at its other end to a pin 86, tends to swing the actuating lever 78 downwardly in a counterclockwise direction as shown in Fig. 2, to a limiting position determined by the engagement of the lever with an adjustable stop pin 88. Movement of the actuating lever 78 in a reverse or clockwise direction to the position shown in Fig. 2, causes the cammed upper surface thereof to engage against a bearing surface formed by the upper end of a slot 90 through which the actuating lever 78 extends to raise the upper guard 32 out of engagement with the work. The actuating lever 78 is moved in a clockwise direction to raise the upper guard 32 from the work by means of a nub 92 formed on a collar 94 on the awl bar 23. During the upward movement of the awl bar, the nub 92 engages against the cammed surface formed in the forward edge of the actuating lever 78 to move the lever to its raised position, the lever then being supported in this position by continued movement of the nub 92 onto a flattened surface of the lever 78. During subsequent downward movement of the awl bar 23 and awl 18, the actuating lever 78 is again released and permitted to fall under the influence of its spring 82 to release the slide 44 and upper guard 32 which is forced downwardly under the pressure of the spring 66 to the limiting position determined by the position of the lug 70 with the abutment 72. In order to provide for an independent adjustment of the limiting raised position of the upper guard 32, the pivot pin 80 is provided with an eccentric bearing portion as shown in Fig. 2, upon which the actuating lever 78 is supported to turn.

With this construction and arrangement of the actuating and supporting mechanism for the upper guard 32, it will readily be seen that the upper guard moves between two predeter-

mined positions toward and away from the work, each of these positions being independently adjustable in order to fit the operation of the upper guard to the requirements of the particular work being operated upon. The forward and back adjustment of the upper guard 32 obtained by adjusting the position of the supporting brackets 47 and 48, permits the upper guard to be positioned laterally toward or away from the path of movement of the needle in accordance with the size of needle being employed and the character of the work being operated upon. It has been found, for example, in operation upon shoes having extremely thin soles, that an adjustment of the upper guard 32 close to the needle is desirable in order to permit the needle to strike as deeply as possible into the shouldered edge of the sole.

Another feature of the present invention consists in a modified and improved arrangement of the work support which will particularly adapt the machine for operation on turn shoes composed of extremely thin or fragile material. In this class of work, as best shown in Fig. 4 of the drawing, the stitch receiving channel in the sole takes the form of a ledge which extends substantially at right angles to the exposed surface of the sole. It is an object of applicant's improved construction to provide support for the shoe as closely as possible at both sides of the awl during its downward thrust, and thus to prevent warping or displacement of the between-substance under the thrust of the awl. In previous constructions, and as shown in Fig. 3, a work support has been employed which comprises the stationary support 10 and a movable support 12 which moves with the needle and serves also to assist the needle in the feeding of the work. With such a construction, the work support 12 will be spaced in a position of extreme displacement with respect to the stationary support 10 during the retracting or loop drawing stroke of the needle, and while the awl is moving downwardly through the work. In the modified construction shown in Figs. 4 and 5, the usual movable work support 12 has been replaced by a needle guide element 100 which terminates at a point substantially below the under side of the work. A movable work supporting element 102 is provided formed on a plate or sector 104 carried on a vertical pivot 106 on the stationary work support 10. A small tension spring 108 connected at one end to a stationary pin 110 and at its other end to a pin 112 on the lever 104 tends normally to maintain the movable work supporting element 102 in its operating position. Movement of the lever 104 under the influence of the spring 108 is limited by the engagement of the pin 112 with a fixed abutment on the stationary work support 10.

The construction and arrangement of the work support comprising the members 10 and 102 is such that the needle during its upward or work piercing movement, passes between the work supporting elements 10 and 102, and also between the portions 34 and 39 of the presser foot 16. As the needle is then shifted in the line of feed, the movable portion 39 of the presser foot, and the movable work supporting element 102 are permitted to be moved yieldingly out of the path of the needle. The needle during its work feeding movement passes out of engagement with the movable work supporting member 102 which is thus permitted to return under the influence of its spring 108 to

work engaging position prior to the movement of the awl 18 downwardly through the work. In this manner, a firm support is provided for the work immediately adjacent both sides of the path taken by the awl during its work piercing stroke.

It will be understood that the invention is not limited to the specific embodiment shown, and that various deviations may be made therefrom without departing from the spirit and scope of the appended claims.

What is claimed is:

1. In a machine for sewing the upper to the sole of a shoe of the general type having stitch forming devices which include a work piercing awl and a straight needle movable to feed the work, and devices for supporting the work in position to cause the needle to enter and emerge from the same side of the work, the combination with the needle and awl, of work supporting devices including a presser foot to bear against the upper at the edge of the sole, an upper guard movable toward and away from the work and having work engaging surfaces constructed and arranged to position the upper with relation to the sole edge, and positioning means adapted for positively limiting movement of the upper guard toward the work.

2. In a machine for sewing the upper to the sole of a shoe of the general type having stitch forming devices which include a work piercing awl and a straight needle movable to feed the work, and devices for supporting the work in position to cause the needle to enter and emerge from the same side of the work, the combination with the needle and awl, of work supporting devices including a presser foot to bear against the upper at the edge of the sole, an upper guard movable between limiting positions of engagement with and away from the work surface and having work engaging surfaces constructed and arranged to position the upper with relation to the sole edge, means for moving the upper guard to said limited position away from the work surface during the work feed, and positioning means independently adjustable for determining each of said positions.

3. In a machine for sewing the upper to the sole of a shoe of the general type having stitch forming devices which include a work piercing awl and a straight needle movable to feed the work, and devices for supporting the work in position to cause the needle to enter and emerge from the same side of the work, the combination with the needle and awl, of work supporting devices including a presser foot to bear against the upper at the edge of the sole, a work support, means for lifting the presser foot to release the work during the work feed, an upper guard movable into and out of engagement with the shoe and having work engaging surfaces constructed and arranged to position the upper with relation to the sole edge, and means for moving the upper guard to a predetermined position away from the work during the work feed comprising an upper guard actuating lever, means for rocking the lever to raise the upper guard, and an eccentric pivot for the lever angularly adjustable to determine the retracted position of the upper guard from the work.

4. In a machine for sewing the upper to the sole of a shoe of the general type having stitch forming devices which include a work piercing awl and a straight needle movable to feed the work, and devices for supporting the work in position to cause the needle to enter and emerge from

the same side of the work, the combination with the needle and awl, of work supporting devices including a presser foot to bear against the upper at the edge of the sole, an upper guard movable between limiting positions toward and from the work surface and having work engaging surfaces constructed and arranged to position the upper with relation to the sole edge, spring means for moving the upper guard toward the work, an adjustable stop for adjustably determining the limiting position of the upper guard toward the work, and means for moving the upper guard away from the work during the work feed having provision for adjustment to adjustably determine the limiting position of the upper guard away from the work.

5. In a machine for sewing the upper to the sole of a turn shoe having a stitch receiving channel formed in the sole, the combination of stitch forming and work feeding devices including an awl having a work piercing and retracting movement, a needle movable to feed the work, devices arranged to support the work in position to cause the needle to emerge from the same side of the work, comprising a work support for engagement with the stitch receiving channel, a presser foot to bear against the upper at the edge of the sole, means for lifting the presser foot to release the work during work feed, an upper guard movable between limiting positions toward and away from the work surface and having work engaging surfaces constructed and arranged to position the upper with relation to the sole edge, means for moving the upper guard away from the work during the work feed, and supporting means on which the upper guard is movable toward and away from the work, having provision for adjustment transversely of the direction of feed.

6. A machine for sewing the upper to the sole of a shoe having, in combination, a needle and an awl disposed at opposite sides of the work, means for actuating the needle to feed the work, devices cooperating with the needle to form the stitch, devices arranged to support the work in position to cause the needle to enter and emerge from the same side of the work comprising a presser foot arranged to bear against the upper at the edge of the sole, and a work support to engage against a stitch receiving channel formed in the sole, said work support comprising a fixed portion engaging the shoe in the line of feed at that side of the needle and awl path remote from the completed stitches of the seam, a movable portion in engagement with the work in close proximity to the other side of the needle and awl path, and supporting means for said movable portion arranged to cause said movable portion to be moved out of the path of movement of said needle during the feeding movement thereof, and thereafter to be re-positioned to support the work against the work piercing stroke of the awl.

7. A machine for sewing the upper to the sole of a shoe having, in combination, a needle and an awl disposed at opposite sides of the work, means for actuating the needle to feed the work, devices cooperating with the needle to form the stitch, devices arranged to support the work in position to cause the needle to enter and emerge from the same side of the work comprising a work support to engage a stitch receiving channel formed in the sole, and a presser foot arranged to bear against the upper at the edge of the sole, each of said work support and presser foot comprising a fixed portion engaging the shoe in the line of feed at that side of the needle and awl

path remote from the completed stitches of the seam, a movable portion for engagement with the work in close proximity to the other side of the needle and awl path, and supporting means for said movable portion including a yieldable holding element arranged to permit movement of said movable portion out of the path of movement of said needle during the feeding movement thereof.

8. A machine for sewing the upper to the sole of a shoe having, in combination, stitch forming and work feeding devices including a needle and an awl disposed at opposite sides of the work, devices arranged to support the work in position to cause the needle to enter a stitch receiving channel in the sole and to emerge from the upper at the same side of the work comprising a work support to engage in the stitch receiving channel, and a presser foot arranged to bear against the upper at the edge of the sole, and means for actuating the needle while through the work to feed the work, said work support having a fixed portion at one side of the needle path, and a portion at the other side of the needle path supported to swing on a vertical pivot for movement

out of the path of the needle during the feeding movement thereof, and means for holding said movable portion yieldingly in its work supporting position.

5 9. A machine for sewing the upper to the sole of a shoe having, in combination, stitch forming and work feeding devices including a needle, devices arranged to support the work in position to cause the needle to enter a stitch receiving channel in the sole and to emerge from the upper at the same side of the work, comprising a work support to engage in the stitch receiving channel, and a presser foot arranged to bear against the upper at the edge of the sole, and means for actuating the needle while through the work to feed the work, said work support having a fixed portion at one side of the needle path, and a portion at the other side of the needle path supported to turn on a vertical pivot to be moved yieldingly out of the path of the needle during feeding movement thereof, and a needle guide supported to move with the needle during the feeding and return movements thereof.

EDWARD QUINN.
